UNITED STATES PATENT OFFICE.

JOSEPH H. POPE, OF BROCKTON, MASSACHUSETTS, ASSIGNOR, BY MESNE ASSIGNMENTS, TO
UNITED SHOE MACHINERY COMPANY, A CORPORATION OF NEW JERSEY.

HEEL-ATTACHING MACHINE.

No. 884,524.

Specification of Letters Patent.

Patented April 14, 1903.

Application filed May 24, 1898. Serial No. 681,610.

To all whom it may concern:

Be it known that I, JOSEPH H. POPE, of Brockton, in the county of Plymouth and State of Massachusetts, have invented an improvement in Heel-Attaching Machines, of which the following description, in connection with the accompanying drawings, is a specification, like letters on the drawings representing like parts.

The present invention relates to heel attaching machines and is shown embodied in a machine for attaching loaded heels. As will be obvious, however, from the following description, certain features of the invention are capable of advantageous use in connection with machines for attaching heels which have not been previously loaded with nails.

In the operation of attaching a heel to a shoe the pressure exerted upon the heel in the direction of its thickness by the heel attaching machine tends to expand the heel in a direction transverse to the line of pressure. It is desirable that rearward displacement of the heel by its expansion be avoided since such displacement causes the heel to be thrown out of proper relation to the sole of the shoe to which it is to be attached. To this end in the present embodiment of the invention there is provision for preventing expansion of the heel in a rearward direction, such expansion as may occur being caused to take place in the direction of the breast of the heel. This provision may conveniently comprise a fixed abutment or gage which is arranged to engage the rear end of the heel and a yielding gage arranged to engage the breast of the heel.

The present invention also includes means whereby gages for positioning the heel in proper relation to the heel seat may be relatively adjusted to accommodate different sizes of heels. A convenient and preferred construction comprises a plurality of gages arranged for relative movement to permit the insertion of a heel between them, a spring arranged to hold the gages yieldingly from separating movement, and means for adjusting the distance between said gages without varying the action of the spring. According to this construction the tension of the spring is not affected by any adjustment which may be given the gages, said gages exerting a uniform pressure upon the heel regardless of their adjustment. In the construction here-

in shown relative adjustment of the gages is secured by the manipulation of a single controlling device.

The mechanism herein illustrated comprises a heel box upon which a back gage and breast gage are mounted, the breast gage being arranged for yielding movement away from the back gage. A driver plate is arranged for movement within the heel box and is adapted to sustain upon its acting face the projecting head ends of the nails of a loaded heel to be attached to a boot or shoe. The gages for the rear and the breast of the heel are arranged in a plane vertically removed from the normal position of the acting face of the driver plate and preferably provision is made for adjusting the relation between said gages and the face of said plate in order that the gages may engage the heel at the points desired.

Other features of the invention will be hereinafter described and defined in the claims.

Figure 1, in elevation, represents a sufficient portion of a heel-attaching machine embodying my improvements to enable my invention to be understood; Fig. 2 is a much enlarged top or plan view of the heel-box and the parts for moving it; Fig. 3 is a section on the scale represented in Fig. 1, but in the line x, of Fig. 2; and Fig. 4 represents, in side elevation a part of the framework and a means for vertically reciprocating the die-bed spindle.

The framework A, and the die-bed spindle E⁴ adapted to be reciprocated vertically in a suitable guide E³, are and may be substantially such as represented in U. S. Patent No. 446,383, dated Feb. 10, 1891. The upper end of this reciprocating die-bed spindle E⁴ has an attached plate a, upon which is mounted by suitable screws a¹, a cross-head a². This cross-head has a hole in which is placed a post a³, said post being held in a fixed position by a suitable set-screw a⁴ inserted through the cross-head.

The post has fixed or integral with its upper end, a head a⁵ provided preferably with a steel face-plate a⁶, said plate constituting a driver-plate. Prior to inserting the post into the cross-head, said post is passed through a hole in the heel-box b, and through a suitable spring c surrounding a depending sleeve of said box, so that when the set-screw

a^4 is turned in to hold the post in fixed position with relation to the die-bed spindle, the spring c acts normally to elevate the heel-box as far as the head a^5 will permit.

5 The heel-box has attached to it by suitable screws b' , an abutment or bar b^2 , represented herein as notched to position the curved or rounded back part of the heel to be attached.

The box has two ears b^3 and b^4 through which 10 is extended loosely a screw-rod b^5 , to which is united by a pin d the breast-gage d' , said breast-gage being normally pressed toward the bar b^2 by means of a spring d^2 surrounding said screw-rod and acting at one end 15 against the ear b^4 , the opposite end of said spring acting against a nut e screwed onto the threaded part of said screw-rod, and acting by its opposite end against the ear b^3 .

By rotating the nut e , the screw-rod may 20 be moved in one or the other direction in the ears in order to adjust the inner edge of the breast-gage to contact properly with the breast of the heel to be attached to the shoe. In the rotation of this nut to shift the screw- 25 rod longitudinally and thereby adjust the breast-gage, one end of the nut is always kept against the ear b^3 and the screw-rod is moved in one or the other direction through the spring d^2 and through the ears b^3 , b^4 , but 30 the other end of the nut in any or all adjustments of the rod acts just the same at all times upon the spring. By this arrangement said spring in the different adjustments of the screw-rod in positioning the 35 breast-gage acts uniformly in yielding to expansion of the heel due to pressure exerted thereon in attaching the heel to the sole of the shoe held by any usual jack, the breast of the heel during the attaching operation moving forward more or less and taking with it 40 the spring-held breast-gage.

The screw-rod has, as herein shown, a milled end d^x that may be engaged at any time by the operator when it is desired to 45 draw the screw-rod in the direction of the arrow Fig. 2 to move the breast-gage in order that the heel to be attached to the sole may be inserted in the heel-box with its rounded end against the bar or gage b^2 , releasing the 50 screw-rod permitting said spring immediately to move the breast-gage against the breast of the heel.

The end of the breast-gage farthest from the screw-rod enters a suitable guideway cut 55 in the inner side of the heel-box b , said guideway being shown at the left in Fig. 1. The bar or gage b^2 may be adjusted if desired to position it for heels of different sizes.

The construction herein shown as embodying 60 my invention is particularly intended for use in attaching a loaded heel, that is a heel having driven into it the series of nails to be used to attach the heel to the heel-seat end of the sole, the points of the nails not extending 65 through the heel, but the head ends of said nails

project more or less, that depending upon the distance the manufacturer may desire to drive the nails through the sole and into the inner-sole etc., used in the particular shoe being made.

70 The heel-box has an adjusting-screw f , see Fig. 1, the upper end of which acts against the head a^5 of the post a^3 , and by turning said screw the heel-box and its attached breast-gage may be adjusted vertically with 75 relation to the head a^5 to put the breast-gage and back-bar at the desired distance above the driver-plate a^6 on which rests the heads of the attaching nails.

The adjusting-screw f will, in practice, be 80 turned to occupy different positions according to the length of the undriven part of the nails projecting from the tread-end of the heel, for, in practice, it is contemplated that the back-bar or gage b^2 and the breast-gage 85 d' will contact with the top or outer-lift at the tread-end of the heel. Under these conditions heels having been positioned in the heel-box with the heads of the nails resting upon the driver-plate a^6 , the die-bed spindle 90 E^4 being in its lowered position, the said die-bed spindle will be raised in usual manner and in such movement the seat-end of the heel will soon contact with the heel-seat of the sole and the heel will be forced firmly 95 against the sole, and during the further rising movement of the die-bed spindle the driver-plate a^6 acting on the heads of the partially driven nails will force them further through the heel and into the sole, the upward movement of the heel-box during this driving operation being arrested, and finally the driver-plate a^6 will come substantially up to or 100 flush with the underside of the bar or gage b^2 and breast-gage, at which time the nailing 105 operation will have been completed and the die-bed spindle will be then lowered and said bar or gage and the breast-gage will be drawn off readily from the end of the heel.

Having described my invention, what I 110 claim and desire to secure by Letters Patent, is:—

1. In a heel-attaching machine, a heel-box, a device to position a rear part of the heel, an adjustable breast-gage, and mechanism including a spring whereby a uniform yielding pressure is exerted on said breast-gage in its different adjustments, combined with a driver-plate located in said heel-box, and means to actuate said driver-plate and heel-box, to force the heel against the sole of the shoe to which the heel is to be attached, further movement of the driver-plate while the heel-box is at rest causing the nails to be driven through the heel into the sole of the 120 shoe.

2. A heel-box having unyielding means to position the rear part of a heel, a breast-gage, and means to adjust said breast-gage to adapt the heel-box to the size of the heel used, 130

and a spring to hold said breast-gage yieldingly in position, combined with a driver-plate, and means to actuate it to drive nails through said heel into the sole of a shoe, substantially as described.

5. 3. A heel-box having guiding ears, a screw threaded rod mounted loosely in said ears and provided with a breast-gage, a nut applied to a threaded part of said rod, and a spring surrounding said rod at one end of said nut, said nut and spring being located between the said ears, said rod being adjustable by means of said nut to vary the position of the breast-gage for heels of different sizes, but without at all affecting the tension of the spring, the latter always permitting the breast-gage to yield uniformly to pressure on the heel in whatever position the breast-gage may be adjusted, substantially as described.
10. 4. A heel-box having unyielding means to position the rear part of a heel, a breast-gage, means to adjust it longitudinally of the heel, and means to hold said adjusted breast-gage yieldingly in position.

15. 5. In a heel-attaching machine, a heel-box, a driver plate vertically movable in said heel-box, having an acting flat face arranged to form the bottom of the heel-box cavity, and gages for the rear and breast of a heel, respectively, carried by the heel-box, and arranged in a plane vertically removed from the normal position of said acting face, said gages being mounted to be relatively 20 adjustable to adapt the heel-box to heels of different sizes.

25. 6. In a machine for attaching loaded heels, a driver-plate to receive the protruding head ends of the nails of a loaded heel, a fixed abutment for positioning the rear end of the heel, a yielding gage for the breast of the heel, and means whereby said yielding gage may be adjusted to adapt the same for heels of varying sizes.

30. 7. In a heel-attaching machine, a device to position the rear part of a heel, an adjustable breast-gage, and mechanism including a spring whereby a uniform yielding pressure is exerted on said gage in different adjustments.

35. 8. In a heel-attaching machine, a heel-box, a driver-plate, vertically movable in said heel-box, having an acting flat face arranged to form the bottom of the heel-box cavity, gages for the rear and breast of a heel, respectively, carried by the heel-box, arranged in a plane vertically removed from the normal position of said acting face, and mounted to be relatively adjustable to adapt the heel-box to heels of different sizes, and a spring arranged to permit a relative yielding movement of said gages.

40. 9. A heel-box to receive a loaded-heel, a plurality of ears carried by said heel-box, a

device to position the back-part of the heel, a screw-rod guided by said ears and provided with a breast-gage, a spring acting to hold said screw-rod in a yielding manner, and a nut engaging the threaded part of said screw-rod 70 and interposed between the opposite end of said spring and one of said ears, whereby by turning said nut on said screw-rod the breast-gage may be adjusted relatively to the device for positioning the back part of the heel, 75 said spring acting normally to hold the breast-gage against the breast of the heel.

10. 10. In a heel-attaching machine, a heel-box, a driver-plate vertically movable in said heel-box, having an acting flat face arranged 80 to form the bottom of the heel-box cavity, gages for the rear and breast of a heel, respectively, carried by the heel-box, and arranged in a plane vertically removed from the normal position of said acting face, said gages being mounted to have a relative yielding movement to permit the insertion of a heel between them.

11. 11. A heel-attaching machine comprising a fixed device to position the outer edge of 90 the heel, a breast-gage, a spring acting normally to maintain the breast-gage in contact with the heel breast, and means for adjusting said breast-gage to heels of different lengths without varying the tension of the spring. 95

12. 12. In a heel-attaching machine, a heel-box, a driver-plate, vertically movable in said heel-box, having a flat acting face arranged to form the bottom of the heel-box cavity, gages for the rear and breast of a heel, 100 respectively, adjustably carried by the heel-box, and arranged in a plane vertically removed from the normal position of said acting face, and means permitting the normal position of the driver-plate with relation to 105 the gages to be varied.

13. 13. A heel-holder having means to position one end of a heel, a gage to act on the other end of the heel, carrying means for said gage, means to move said carrying means to 110 adjust said gage toward and from said positioning means for heels of different sizes, and a spring mounted to act with substantially uniform force to move said gage toward the means for positioning the end of the heel 115 whatever the position occupied by said gage.

14. 14. A heel-box having means to position the rear part of a heel, a breast-gage, a screw-threaded rod, with which said gage is connected, a spring and a nut mounted on said 120 rod, said nut being adjustable with relation to said rod, and ears carried by said box for guiding said rod, one of said ears acting against said nut, and the other against said spring, the rotation of the nut on the rod adjusting the position of the breast-gage with relation to the heel-box, the spring acting substantially uniformly in all positions of the breast-gage. 125

15. 15. In a machine of the class described, a 130

plurality of gages for positioning a heel arranged for relative movement to permit the insertion of the heel between them, a spring arranged to hold one of the gages yieldingly in engagement with the heel, and means for adjusting said last-named gage without varying the action of said spring.

In testimony whereof, I have signed my name to this specification, in the presence of two subscribing witnesses.

Corrections in Letters Patent No. 884,524.

It is hereby certified that in Letters Patent No. 884,524, granted April 14, 1908, upon the application of Joseph H. Pope, of Brockton, Massachusetts, for an improvement in "Heel-Attaching Machine," an error appears in the printed specification requiring correction, as follows: In line 54, page 3, the words "to form the bottom of the heel-box," should be stricken out; and that the said Letters Patent should be read with this correction therein that the same may conform to the record of the case in the Patent Office.

Signed and sealed this 26th day of May, A. D., 1908.
